UNITED STATES PATENT OFFICE.

HENRY C. TROST, OF EL PASO, TEXAS.

AUTOMATIC INTERLOCKING ATTACHMENT FOR WINDOW SASHES.

Application filed April 6, 1923. Serial No. 639,353.

To all whom it may concern:

Be it known that I, HENRY C. TROST, a citizen of the United States of America, and a resident of El Paso, county of El Paso, and State of Texas, have invented certain new and useful Improvements in Automatic Interlocking Attachments for Window Sashes, of which the following is a full and clear specification.

10 This invention has relation to the class of devices particularly covered by my Patent No. 1,439,585, dated December 19, 1922, and the object of my present invention is to so construct the devices that they 15 may be manufactured at a minimum cost, as more fully hereinafter set forth.

In the drawing—

Fig. 1 is a side view of a portion of a window showing my invention applied 20 thereto;

Fig. 2 is a detail perspective view of one of the trip-plates.

Fig. 3 is a plan of the trip-plate blank, from which the device is stamped up;

25 Fig. 4 is a detail perspective view of the locking member.

Referring to the drawing annexed by reference-numerals, 5 designates the base-plate of the tripping member, which is 30 fastened, in a diagonal position on the sash, by a series of screws 6. Projecting outwardly from the longitudinal edges of this base-plate are two flanges 7, and projecting laterally from the respective ends of these 35 flanges are cam-lugs 8. These trip-plates are used in pairs, the plates of each pair being arranged in the sashes in reversed relation, as fully set forth in my former patent. The flanges 7 form a diagonal channel and the parts 8 form cam-lugs, and these parts function as set forth in my aforesaid 40 patent.

By making the trip-plate in the manner set forth, it will be observed that it may be 45 stamped up from a single piece of sheet-metal properly shaped, thus greatly simplifying the method of manufacturing the trip-plate and keeping its cost down to a minimum.

50 The locking member, carried by the other sash as usual, consists of a single piece of sheet-metal stamped to shape, one end 9 being adapted to be secured to the sash and the other end 10 being adapted to project 55 away from the edge thereof and afford a support or hanger for a pendulum locking

device. In the present instance, this locking device consists of a metal rod bent to form two pendent members 11 and 12 and an intermediate portion 13 which extends 60 through a hole in the support 10 and forms the journal of the device, the free end of the member 11 having its extreme end bent to form a lug 14 which stands at right-angles to the face of the supporting member 10. This locking member hangs loosely 65 on the journal 13 and in its normal position the two members 11 and 12 stand vertical. The lock-lug 14 cooperates with the cam hooks 8 and the channel of the 70 trip-plate in the manner set forth in my former patent. The pendent member 12 serves as a weight to ensure the tendency 75 of the locking member to normally swing to a vertical position. It will be observed that this locking device may be made at an extremely low cost, consisting, as it does, of but two parts, each of which may be readily and inexpensively made. The device also affords maximum strength in that it is 80 adapted to stand severe strains without being rendered inoperative. One of the factors which renders this locking device easily made and reliable in operation is 85 that I do away with separate pivots for the pendulum locking member.

What I claim is:

1. An automatic interlocking attachment 90 for window sashes of the type set forth embodying a tripping member adapted to be attached to one of the sashes and a locking member adapted to be attached to the other sash, the locking device consisting of a supporting plate adapted for attachment to the sash and a pendulum locking member 95 pivotally mounted thereon, said locking member consisting of a lug-carrying member on one side of the support and a pendent weight on the other side of the support.

2. An automatic interlocking attachment 100 for window sashes of the type set forth embodying a tripping member adapted to be attached to one of the sashes and a locking member adapted to be attached to the other sash, the locking device consisting of a supporting plate adapted for attachment to the sash and a pendulum locking member 105 pivotally mounted thereon, said locking member consisting of a rod bent to form two pendent portions having an intermediate 110 journal, one of said portions being provided at its free end with a lateral lock-lug.

3. An automatic interlocking attachment for window sashes of the type set forth embodying a tripping member adapted to be attached to one of the sashes and a locking member adapted to be attached to the other sash, each of these tripping members embodying a base-plate, a pair of diagonal flanges forming a diagonal channel, and a lateral hook formed on the end of each of

these channels, the whole being bent up ¹⁰ from a single piece of sheet-metal.

In testimony whereof I hereunto affix my signature.

HENRY C. TROST.
